US0D1091129S

(12) **United States Design Patent** (10) Patent No.: **US D1,091,129 S**
(45) Date of Patent: ** Sep. 2, 2025

(54) **EARPHONE CASE**

(71) Applicant: **HUAWEI TECHNOLOGIES CO., LTD.**, Guangdong (CN)

(72) Inventors: **Yangbin Xuan**, Shenzhen (CN); **Jie Huang**, Shanghai (CN)

(73) Assignee: **HUAWEI TECHNOLOGIES CO., LTD.**, Shenzhen (CN)

(**) Term: **15 Years**

(21) Appl. No.: **29/869,138**

(22) Filed: **Dec. 22, 2022**

(30) **Foreign Application Priority Data**

Jun. 23, 2022 (CN) 202230387679.X

CLAIM

The ornamental design for an earphone case, as shown and described.

DESCRIPTION

FIG. 1 is a front perspective view of an earphone case, showing our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof; and,

FIG. 8 is a back perspective view thereof.

The broken lines in drawings show portions of the earphone case that form no part of the claimed design.

1 Claim, 8 Drawing Sheets
